(57) **CLAIM**

The ornamental design for a back and seat for a chair, as shown and described.

DESCRIPTION

FIG. 1 is a perspective view showing the side, top and front of a back and seat for a chair which forms my new design; FIG. 2 is a perspective view showing the right side, top and rear thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom plan view thereof.

The broken lines represent stitching and the portions of the design that form no part of the claim.
